GREASE GUN

Basil A. Beaver, Minneapolis, Minn., assignor to
Gray Company, Inc., Minneapolis, Minn., a cor-
poration of Minnesota

Application February 4, 1948, Serial No. 144,275

Term of patent 7 years

(Cl. D46—1)

To all whom it may concern:

Be it known that I, Basil A. Beaver, a citizen of the United States, residing at Minneapolis, in the county of Hennepin, State of Minnesota, have invented a new, original, and ornamental Design for a Grease Gun, of which the following is a specification, reference being had to the accompanying drawing, forming part thereof.

Figure 1 is a side elevational view of a grease gun embodying my new design.

Figure 2 is an end elevational view looking from the right of Figure 1.

Figure 3 is a perspective view, on an enlarged scale, showing the barrel and nozzle of the grease gun shown in Figures 1 and 2, in disassembled position.

I claim:

The ornamental design for a grease gun, as shown.

BASIL A. BEAVER.
